ABSTRACT OF THE DISCLOSURE

A process of hydrogenating lube oil fractions having a viscosity in the range of about 50 SUS at 100° F. and about 240 molecular weight at about 6000 SUS at 100° F. and about 500 molecular weight wherein the higher viscosity and higher molecular weight materials are enhanced as to the UV absorptivity at 260 m μ . Specifically, the heavier fractions enhanced in UV are those above about 1000 SUS at 100° F. and above about 360 molecular weight by blending same with a lower viscosity and lower molecular weight material having a viscosity in the range of about 50 SUS at 100° F. and about 240 molecular weight to below about 1000 SUS at 100° F. and below about 360 molecular weight, hydrogenating same over a sulfactive hydrogenation catalyst at a temperature in the range of about 450° to 750° F. and a hydrogen partial pressure of about 100 to 10,000 p.s.i.g. but preferably a temperature in the range of about 475° to 625° F. and a pressure in the range of about 500 to 2000 p.s.i.g., and then separating the two blended oils.

In brief, this application pertains to improvements in hydrogenation of lubricating oils. More specifically, this invention relates to the use of combined crude fractions of widely different viscosities or a lube fraction containing components which cumulatively represent a relatively broad spectrum of viscosities in hydrogenation operations whereby improvements in the lubricating oil are obtained, and particularly in regard to UV absorptivity of the heavier fractions thereof.

Certain lube fractions have been found suitable for many uses for which other lube fractions are not suitable or at least not preferred. Accordingly, some properties thereof are more critical when a particular fraction and a particular use are contemplated.

Traditionally, a crude is fractionated into a plurality of lubricating oil distillates of varying boiling points and viscosity for the particular end use or end uses contemplated. Preparatory to such distillation of wide fractions, however, the crudes are appropriately treated in accordance to their type and characteristics as determined by source of same.

In the case of say naphthenic crudes, for example, they are treated with an alkaline material to remove naphthenic acids which are always found present in such crudes in significant amounts. Illustratively, the naphthenic acids are removed according to the procedures of U.S. Patents 2,770,580 and 2,966,456. Following the distillation, the various fractions are generally hydrogenated to desulfurize, to remove some of the nitrogen present and to selectively hydrogenate the lube oil itself whereby its properties are enhanced.

Paraffinic base crudes receive a different treatment, but conventional for that type such as deasphalting, dewaxing, etc., prior to the hydrogenation. However, the lube fractions once obtained in conventional fashion are hydrogenated for substantially the same reasons and at substantially the same general conditions as indicated for the naphthenic crudes. One specific important property which

2

the hydrogenation is intended to enhance in certain cases, and particularly in rubber oils, is the ultraviolet absorptivity and especially at 260 m μ . Since these various distillate fractions are prepared with different end uses in mind, the hydrogenations have quite naturally been carried out on each fraction.

The foregoing statement is especially true in the case of the naphthenic base lubricating oils, because they are routinely fractionated early in processing into the respective fractions and generally in the caustic distillation stage. For this reason, the present inventive concept of combining certain of the fractions for purposes of the hydrogenation constitutes a particularly unobvious, surprising and unexpected procedure. It is equally unobvious and an unexpected procedure in all cases where the lubricating oil has been fractionated into respective fractions theretofore. It would appear on the surface to be a backward step.

To the accomplishment of the foregoing and related ends, a blend of partially refined lube stock with properties varying in the range from about 200 SUS viscosity at 100° F. and an average molecular weight of about 300 to about 1000 SUS viscosity at 100° F. and an average molecular weight of about 360 and comprised of a mixture of components having viscosities which for simplicity here is broadly stated merely to be in the range of about 50 to about 6000 SUS at 100° F. and of about 240 to 500 average molecular weight respectively, is passed over a hydrogenation catalyst at a temperature within the approximate range of 450° to about 750° F., at a pressure within the approximate range from 100 p.s.i.g. to about 4000 p.s.i.g., in the presence of hydrogen.

It has been mentioned heretofore that in the practice of this invention, the hydrocarbon feed components that are blended are to have a viscosity varying in the range of about 50 to about 6000 SUS at 100° F. (or 32 to 200 SUS at 210° F.), and of about 240 to 500 average molecular weight respectively; however, this is not entirely accurate without further qualification. While the individual components or fractions that blend to form the feed are to fall generally within the foregoing broad range, it is essential that there be substantial amounts of material present which, as isolated fractions, have a SUS viscosity of at least about 1000 SUS at 100° F. and about 360 average molecular weight and below about 6000 SUS at 100° F. and below about 500 average molecular weight respectively. This is so because only the lube fractions above about 1000 SUS at 100° F. in viscosity and 360 average molecular weight have been found to be improved by this invention, and accordingly, in order to fully utilize the present invention there must be some of this material present. The more important benefits of the invention are obtained only under such condition. Other components do not experience any significant disadvantages

from such procedure, however, the important benefits are not attained in such cases and, accordingly, such technique provides no incentive in utilizing feeds of lower viscosity exclusively in such situations. On the other hand, at the same time that some components of a viscosity above 1000 SUS at 100° F. and 360 average molecular weight must be employed in order to obtain the important enhanced beneficiation in properties thereof (as compared to separate hydrogenation of same), it is equally essential that some material having a viscosity below about 1000 SUS at 100° F. and 360 average molecular weight be present to affect the improvement in UV absorptivity of said relatively heavier lube oil fraction, and preferably having a viscosity of about 500 SUS at 100° F. down to about 50 SUS at 100° F. and about 345 down to about 240 average molecular weight respectively.

The individual components of fractions that are blended or otherwise cumulatively comprise the charge to the

hydrogenation zone must possess viscosity characteristics from each of the foregoing ranges, in addition to the most important requirement of the charge stock, that the mixture or blend have a composite viscosity of about 200 SUS viscosity at 100° F. and about 300 average molecular weight to 1000 SUS viscosity at 100° F. and about 360 average molecular weight as previously set forth, but preferably has viscosity of about 250 SUS at 100° F. and about 325 average molecular weight to about 500 SUS at 100° F. and about 345 average molecular weight.

The preferred manner of operation is to operate in liquid phase and to pass the charge stock and hydrogen over the hydrogenation catalyst in downward co-current fashion according to the technique which is frequently referred to as the trickle-phase operation, although on occasion it may be preferred to feed the hydrogen in counter-current fashion.

The hydrogenation catalysts which are suitable are well known in the art and examples are copper, zinc, magnesium, tin, vanadium, tungsten, chromium, molybdenum, manganese, cobalt, iron, nickel, platinum, etc. or their oxides of sulfides or such or mixtures of such metals or their oxides or sulfides. Any of the well-known catalyst carriers may be employed as such carriers as activated carbon, alumina, bauxite, charcoal, clay, kieselguhr, magnesia, pumice, silica, silica-alumina compositions, etc. The preferred catalyst are combinations of cobalt and molybdenum and nickel and molybdenum. Said combinations having been presulfided according to well-known techniques so that they are used in the form of the sulfides on alumina as a carrier.

Although the temperature range broadly suitable is 450° to 750° F., preferably it is within the range of about 475° to 625° F. and still more preferably, the temperature is about 575° to 625° F.

The hydrogen partial pressure range broadly suitable is about 100 to 4000 p.s.i.g., but preferably, the pressure employed is about 500 to 2000 p.s.i.g., and more preferably, 1000 to 1500 p.s.i.g.

The hydrogen employed is preferably a hydrogen stream containing at least about 70 percent hydrogen; however, any hydrogen-rich refinery stream may be employed. Generally, the hydrogen stream is employed in an amount varying from about 10 to 1000 s.c.f./barrel of lubricating oil, and more preferably, about 50 to 300 s.c.f. on the same basis. The space rates may vary over a wide range depending on the design of the reactor and the residence time desired, but generally, such space rates will vary between about 0.25 to 20 volumes of liquid charge per volume of catalyst bed per hour. Of course, in regard to the space rates, any recycle of material is to be considered in determining the foregoing figure. Gas recycle may be employed for example, as set forth in U.S. 2,918,425 or liquid may be recycled either internally (i.e., before any purification) or according to conventional recycle techniques of recovering unconverted partially converted or reacted material and returning same to the reactor.

Following the hydrogenation, the oil is then fractionated into a plurality of lubricating oil distillates of varying boiling points and viscosity. Generally, the properties are for all practical purposes substantially the same as those the same fractions have if hydrogenated separately. There is at least one important exception, however, and this involves an improved UV absorptivity at 260 μ of the fraction or those fractions with a viscosity above about 1000 SUS at 100° F. and about 360 average molecular weight. Following this fractionation, the fractions may be further treated according to the needs of the particular end use intended. For example, they may be extracted with solvents such as furfural, methyl ethyl ketone, etc. They may be instead or in addition treated with clays and/or sulfuric acid.

To facilitate the understanding of the invention, certain details and illustrative embodiments will now be set

forth; however, of course, it is to be fully understood and appreciated that the invention is not limited to the specific conditions or details set forth in these examples, since the process is capable of many modifications and variations and conditions, such modifications and variations being aided, suggested or indicated by the discussion of the process as found herein and the discussions of the trends of the effect of various factors.

EXAMPLE I

10 A Grade A crude mix (a naphthenic base crude) of about 0.89 viscosity-gravity constant was caustic distilled according to the procedure of U.S. Patent 2,770,580. A blend of the fractions were prepared with a viscosity of about 340 at 100° F. and about 47 at 210° F. This blend and hydrogen were continuously fed to a conventional trickle-phase hydrogenation reactor in conventional fashion and was hydrogenated in a continuous operation over a presulfided nickel-molybdenum on alumina catalyst at a pressure of about 1000 p.s.i.g. and at temperature of about 600° F. Fresh feed with a UV absorptivity of about 11.2 was charged at a rate of about 0.5 volume of feed per volume of catalyst per hour and liquid product was recycled at a rate to provide a total liquid space rate of about 4.0 volumes of liquid per volume of catalyst per hour. A make-up stream of 100 percent hydrogen at a rate of approximately 235 s.c.f./bbl. was required. The hydrogenated product was fractionated to provide three separate fractions (see the table below, left-hand side). The heaviest fraction with a viscosity of about 2800 SUS at 100° F. and an average molecular weight of about 396 exhibited the most improvement in UV as compared to separate hydrogenation. This fraction had a UV absorptivity of 4.1.

20 When this same fraction (i.e., of comparable viscosity, about 2800 SUS at 100° F., and about the same average molecular weight, 381) was hydrogenated separately directly from the caustic distillation at the same conditions, it had a UV absorptivity of 4.9, although the other properties were substantially the same as when blended before hydrogenation in accordance with the foregoing run. This is more than 16 percent improvement in UV absorptivity. The other fractions, however, were not found to be sacrificial to the improvement in UV obtained of the higher molecular weight material when the feeds were blended and hydrogenated together as shown by the data below.

	Combined feed stream hydrogenation			Separate feed stream hydrogenation		
	UV of combined feed	Mol wt. of product fractions	UV of product fractions	UV of feed fractions	Mol wt. of product	UV of product fractions
50	11.2-----	268	2.4	7.8	276	2.4
	11.2-----	331	3.2	9.8	333	3.5
	11.2-----	396	4.1	11.2	381	4.9

55 Having now described the invention, many ramifications and modified embodiments will readily occur to those skilled in the art. Insofar as such variations do not depart from the spirit and scope of the invention described in this application, they are intended to be embraced by the appended claims in their broadest construction.

We claim:

1. In a process of hydrogenating lubricating oils having properties varying in the range from about 50 SUS at 100° F. and about 240 molecular weight to about 6000 SUS at 100° F. and about 500 molecular weight with hydrogen over a hydrogenation catalyst, the improvement which comprises charging as feed to said hydrogenation zone a lubricating oil distillate having a composite viscosity in the range of about 200 SUS at 100° F. and about 300 molecular weight to about 1000 SUS at 100° F. and about 360 molecular weight with the further provision that said composite viscosity is obtained as a mixture of at least two distillate fractions wherein at least one of said fractions has a viscosity in the range of about 50 SUS at 100° F. and about 240 molecular weight to

below about 1000 SUS at 100° F. and below about 360 molecular weight and at least one of said fractions has a viscosity of above about 1000 SUS at 100° F. and above about 360 molecular weight up to about 6000 SUS at 100° F. and about 500 molecular weight, and separating said heavier distillate fraction having a viscosity above about 1000 SUS at 100° F. and above about 360 molecular weight from said lower viscosity and lower molecular weight fraction.

2. A process according to claim 1 wherein said hydrogenation with hydrogen over a hydrogenation catalyst is conducted at a temperature within the range of about 450° to 750° F. and at a pressure within the range of about 100 p.s.i.g. to about 4000 p.s.i.g.

3. A process according to claim 2 wherein said hydrogen employed is a refinery hydrogen stream of at least about 70 percent hydrogen.

4. The process according to claim 2 wherein the space rates employed vary from about 0.25 to 20 volumes of liquid oil charge per volume of catalyst bed per hour and about 10 to 1000 standard cubic feed of hydrogen per barrel of liquid oil charge.

5. The process according to claim 4 wherein the oil charge has a composite viscosity in the range of about 250 SUS at 100° F. and about 325 molecular weight to 25 about 500 SUS at 100° F. and about 345 molecular weight.

6. The process according to claim 5 wherein the hydrogenation catalyst employed is a presulfided nickel-tungsten on alumina, nickel-molybdenum on alumina or cobalt-30 molybdenum on alumina catalyst.

10

15

20

25

30

7. The process according to claim 6 wherein the hydrogenation temperature employed is in the range of about 575° to 625° F.

8. The process according to claim 7 wherein the hydrogen partial pressure at which the hydrogenation is carried out is in the range of about 500 to 2000 p.s.i.g.

9. The process according to claim 8 wherein said hydrogenation catalyst is a nickel-molybdenum on alumina catalyst obtained by sulfiding a nickel oxide-molybdenum oxide mixture on alumina wherein nickel oxide is present in an amount equal to about 3 percent and molybdenum oxide is present in an amount equal to about 15 percent, sodium oxide is present in about 0.02 percent by weight and the remainder is alumina.
